ABSTRACT OF THE DISCLOSURE

An absentee line circuit adapter is provided for telephone systems. The adapter re-routes calls to another predetermined line in the same exchange as soon as the subscriber wishing to transfer calls to this line depresses a grounding key. The subscriber may then check to see if re-routing has been established by lifting the handset, at which time a special tone will indicate that from then on calls will be transferred.

The invention relates to a switching system including at least two stations at least one of which includes control signal generator means which when operated control the operation of switching means in the line circuit of said one station in order to allow calls destined for said one station to be diverted towards the associated station.

Such a switching system is known from the British Pat. No. 991,667 and operates in such a way that when said switching means are operated they connect a marker wire of one station to a marker wire of an associated station.

Such a solution is evidently limited to switching systems using markers for the setting up of calls.

A first object of the invention is therefore to provide a more general solution.

According to a first characteristic of the present switching system, said two stations are interconnected by a normally inoperative interconnection circuit which is allowed to become operative under the control of said switching means.

In the above known switching system it is moreover necessary in order to enable said call diversion to be performed, to dial a special number constituting a control signal. The subsequently seized register which receives this number reacts on this signal by disconnecting itself from the calling station. Hence not only a call must be simulated but also the registers must be able to receive said special number and to react in a particular way to the receipt of such a number.

Another object of the invention is therefore to provide a switching system of the above type but which permits a call diversion to be allowed in a simpler manner and without it being necessary to modify the registers.

According to another characteristic of the present switching system the control signal generated by said generator means is constituted by a ground capable of being applied to one of the line wires of said one station.

The above mentioned and other objects and features of the invention will become more apparent and the invention itself will be best understood by referring to the following description of an embodiment taken in conjunction with the accompanying drawings wherein FIGS. 1 to 3 arranged one below another represent a schematic diagram of a switching system according to the invention.

The switching system shown is part of a telephone switching system and includes three subscriber stations S1, S2, S3 the pairs of output wires of which are connected to the pairs of first input terminals X11, X12; X21, X22; X31, X32 of the respective line circuits I1, I2, I3 which further each have three second input terminals Y11, Y12, Y13; Y21, Y22, Y23; Y31, Y32, Y33 respectively. The latter terminals are connected in the arcs of line finder/final selector switches (not shown) included in the above telephone switching system or exchange. Each of the pairs of second input terminals Y11, Y12; Y21, Y22; Y31, Y32 of the line circuits I1, I2, I3 is coupled to the respective following station S2, S3, S1 via a pair of contacts d11, d12; d21; d22; d31, d32 of an interconnecting relay D1r, D2r, D3r included in the respective line circuit I1, I2, I3 and the break contacts of a pair of change-over contacts b23, b24; b33, b34; b13, b14 of a control relay B1r, B2r, B3r included in these respective line circuits. The make contacts of these pairs of changeover contacts b13, b14; b23, b24; b33, b34 are further connected to the break contacts of the pairs of change-over contacts b23, b24; b33, b34; b13, b14 via leads p, q; r, s and t, u respectively.

The line circuits I1, I2 and I3 are identical and therefore only the line circuit I1 is described in detail hereinafter, the elements included in these line circuits being characterized by the indicia 1, 2 and 3 respectively.

The pair of terminals X11, X12 of the line circuit I1 is coupled to the pair of terminals Y11, Y12 thereof via the pair of wires a1, b1 and the make contacts of the pair of change-over contacts e11, e12 of an interrupting relay E1r. The break contacts of these change-over contacts e11, e12 are branched in parallel and connected in series with the make contact a11 of a repeater relay A1r and with a resistor R12 between the pair of terminals Y11 and Y12. The test terminal Y13 is connected to ground via the break contact of a change-over contact g11 of an inhibiting relay G1r and the winding of a seizure relay F1r and to battery via the make contact of this change-over contact g11 and a resistor R11.

The terminal X11 is connected to ground via lead l11, break contact e14 of interrupting relay E1r, break contact d34 of interconnecting relay D3r of line circuit I3, parallel connected break contacts b311 of control relay B3r of line circuit I3 and d26 of interconnecting relay D2r of line circuit I2, break contact of change-over contact b11 of control relay B1r and winding of repeater relay A1r. The make contact of the latter change-over contact b11 is connected, on the one hand, to an inhibiting circuit M via the winding of acknowledgement relay C1r and lead m1 and, on the other hand, to terminal G via make contact c11 of this acknowledgement relay C1r and capacitor C1. Hereby it should be noted that all the terminals G of the line circuits I1, I2, I3 are joined together and connected to an acknowledgement signal generator (not shown). The lead m1 is also connected to one end of the winding of relay D1r, the other end of this winding and the one end of the winding of relay E1r being connected to ground via make contact f11 of relay F1r. The other end of the winding of relay E1r is connected to battery via break contact b12 of relay B1r.

The terminal X12 is connected to battery via lead l12, break contact e13 of relay E1r, break contact d33 of relay D3r of line circuit I3, parallel connected break contacts d25 of relay D2r of line circuit I2 and b310 of relay B3r of line circuit I3, and the winding of relay B1r.

The winding of the above inhibiting relay G1r is connected between battery and ground in series with the following parallel connected circuits:

Make contact f23 of relay F2r of line circuit I2 in series with a parallel circuit one branch of which com-

prises make contact b_{15} , while the other branch comprises the series connected make contacts b_{212} and b_{38} of relays B_{2r} and B_{3r} respectively;

Make contact f_{32} of relay F_{3r} of line circuit I_3 in series with a parallel circuit one branch of which comprises make contact b_{39} of relay B_{3r} , while the other branch comprises the series connected make contacts b_{16} and b_{213} of relays B_{1r} and B_{2r} respectively.

The above inhibiting circuit M comprises three change-over contacts b_{17} , b_{27} , b_{37} of the respective control relays B_{1r} , B_{2r} , B_{3r} included in the line circuits I_1 , I_2 , I_3 respectively. The fixed contacts of these change-over contacts are joined together and connected to battery, whereas the other fixed contacts thereof are connected to the leads m_1 , m_2 , m_3 of the respective line circuits I_1 , I_2 , I_3 . The movable armatures of the change-over contacts b_{17} , b_{27} , b_{37} are joined together.

From the above it follows that the second input terminals of the line circuit associated with each station (e.g. S_1) are connected to an adjacent station (e.g. S_2) by a normally inoperative interconnecting circuit which is operated by the closure of a pair of d contacts and to yet another station by a normally inoperative interconnecting circuit which is operated by the closure of a pair of d contacts and the operation of a pair of b contacts. For instance, the input terminals Y_{11} , Y_{12} of line circuit I_1 may be connected to station S_2 by the closure of contacts d_{11} and d_{12} and to station S_3 by the closure of contacts d_{11} and d_{12} and by the operation of contacts b_{23} and b_{24} .

The stations S_1 , S_2 , S_3 are identical and each includes a telephone subset (not shown) comprising a respective cradle make contact s_1 , s_2 , or s_3 which closes the respective line loop upon the telephone handset being lifted off. A control key K_1 , K_2 , K_3 is connected to the line wire leading to the respective terminal X_{12} , X_{22} , X_{32} and when actuated it applies a control signal, constituted by a ground, to the respective one of these terminals.

The operation of the above switching system is described in detail hereinafter. Initially it is supposed that all the contacts are in the position shown.

When calls destined for station S_1 must be diverted to station S_2 the control key K_1 is actuated due to which relay B_{1r} is energized as follows: ground, control key K_1 , terminal X_{12} , lead l_{12} , contacts e_{13} and d_{13} , contacts d_{25} and b_{310} in parallel, winding of relay B_{1r} , battery.

The energized relay B_{1r} changes the position of its contacts b_{11} to b_{113} and more particularly of b_{11} to b_{16} in line circuit I_1 , of b_{17} in inhibiting circuit M , of b_{18} to b_{111} in line circuit I_2 and of b_{112} and b_{113} in line circuit I_3 .

The contacts b_{11} , b_{15} , b_{16} and b_{17} in their work position (i.e. in a make or break position) prepare the operation of the acknowledgement relay C_{1r} , of the inhibiting relay G_{1r} and of the interconnecting relay D_{1r} respectively. The contact b_{12} in its work position (i.e. in a make or break position) prevents the operation of interrupting relay E_{1r} so that the interconnection of station S_1 to the exchange is rendered impossible. The contacts b_{13} and b_{14} in their work position connect the leads t , u to the leads p , q thus preventing signals from arriving in station S_1 via contacts b_{13} , b_{14} . In line circuit I_2 the contacts b_{18} and b_{19} in their work position prepare the operation of inhibiting relay G_{2r} , whereas the contacts b_{110} and b_{111} in their work position open in the operation circuits of the control relay B_{2r} and of the repeater relay A_{2r} respectively. Finally, in line circuit I_3 the change of position of contacts b_{112} and b_{113} has no effect on the condition of the inhibiting relay G_{3r} .

After he has actuated control key K_1 a subscriber at station S_1 may positively reassure himself that calls towards this station S_1 will be diverted towards station S_2 by lifting his telephone handset. As a result of the actuation of control key K_1 , the acknowledgement relay C_{1r} is energized as follows: battery, break contacts of change-

over contacts b_{27} and b_{37} in parallel, contact b_{17} , lead m_1 , winding of relay C_{1r} , contacts b_{11} , b_{311} , d_{26} , d_{34} , e_{14} , lead l_{11} , terminal X_{11} , cradle contact s_1 , control key K_1 , ground. The closure of contact c_{11} causes an acknowledgement signal to be applied to station S_1 via capacitor C_1 from the signal generator connected to terminal G .

When a call is made towards station S_1 a connection is set up in the exchange to the terminals Y_{11} , Y_{12} and Y_{13} via a line finder/final selector switch in a classical and therefore not shown manner. Subsequently a ringing signal is applied to terminals Y_{11} and Y_{12} , whereas a seizure signal constituted by a battery is simultaneously applied to test terminal Y_{13} . This ringing signal is not able to reach station S_1 due to terminals Y_{11} , Y_{12} , being disconnected from terminals X_{11} , X_{12} by contacts e_{11} , e_{12} . By the seizure battery the seizure relay F_{1r} is energized as follows: battery at test terminal Y_{13} , contact g_{11} , winding of relay F_{1r} , ground.

The operated relay F_{1r} closes its make contacts f_{11} , f_{12} and f_{13} in line circuits I_1 , I_2 and I_3 respectively. In line circuit I_1 the interconnecting relay D_{1r} is energized as follows: ground, contact f_{11} , winding of relay D_{1r} , contact b_{17} in its work position, contacts b_{27} and b_{37} in parallel, battery. By the closure of contacts d_{11} and d_{12} the terminals Y_{11} , Y_{12} are connected to the wires a_2 , b_2 leading to the station S_2 so that the above ringing signal applied to the terminals Y_{11} and Y_{12} is diverted towards the latter station S_2 . When the subscriber of station S_2 subsequently lifts his telephone handset he is in communication with the calling subscriber. By the opening of contacts d_{13} and d_{14} in line circuit I_2 the relays B_{2r} and A_{2r} are disconnected from the station S_2 so that the above ringing signal cannot influence the condition of these relays. The opening of contacts d_{15} and d_{16} in line circuit I_3 affect the operating circuits of relays B_{3r} and A_{3r} in line circuit I_3 but does not prevent these relays from being energized.

In line circuit I_2 the inhibiting relay G_{2r} is operated as follows upon relay F_{1r} having been energized: battery, winding of relay G_{2r} , contacts f_{12} and b_{19} , ground. Due to this the test terminal Y_{23} is connected to battery via contact g_{21} so that it is rendered busy thus preventing calls made towards station S_2 via terminals Y_{21} and Y_{23} to reach this station.

In line circuit I_3 the closure of contact f_{13} has no effect on the condition of inhibiting relay G_{3r} so that calls can still be made towards station S_3 via terminals Y_{31} and Y_{32} .

From the above it follows that when in station S_1 control key K_1 is actuated the calls made to station S_1 are diverted to station S_2 to which no direct calls can then be made.

In case control key K_1 has not been actuated calls can be made from and towards station S_1 . Indeed, when a subscriber in station S_1 then lifts his handset to make a call the repeater relay A_{1r} is energized as follows: ground, winding of relay A_{1r} , contacts b_{11} , d_{26} , b_{311} , d_{34} , e_{14} , lead l_{11} , terminal X_{11} , cradle contact s_1 , terminal X_{12} , lead l_{12} , contacts e_{13} , d_{33} , d_{25} , b_{310} , winding of relay B_{1r} , battery.

Relay B_{1r} is however not operated since its winding has a high impedance with respect to that of relay A_{1r} . Consequently the terminals Y_{11} and Y_{12} are interconnected via break contact e_{11} , contact a_{11} and resistor R_{12} , so that the closure of cradle contact s_1 is so to say repeated due to which the call is effectively initiated.

When a call is made towards station S_1 wherein control key K_1 is not operated the seizure relay F_{1r} is energized by a seizure signal applied to test terminal Y_{13} in the same manner as described above when control key K_1 is actuated. But instead of relay D_{1r} the interrupting relay E_{1r} is energized as follows: battery, contact b_{12} , winding of relay E_{1r} , contact f_{11} , ground. The contacts e_{11} and e_{12} in their work position connect the terminals

Y11 and **Y12** to the station **S1** so that the ringing signal, which is applied to these terminals at the moment said seizure signal is applied to test terminal **Y13**, operates the ringing circuit of the subset included in station **S1**. By the opening of contacts **e13** and **e14** the relays **B1r** and **A1r** are disconnected from the wires **a1** and **b1** so that the condition of these relays cannot be influenced by the above ringing signal.

Obviously calls are possible from and towards station **S2** independently from the position of control key **K1** and on condition that no call is being made towards station **S1** when control key **K1** is actuated. Calls are also possible from and towards station **S3**.

In case not only control key **K1** but also control key **K2** in station **S2** has been actuated calls towards station **S1** are diverted towards station **S3** on condition that key **K3** has not been operated previously, as will be described hereinafter.

In line circuit **I1** the relays **B1r**, **D1r** and **F1r** are energized in the manner described above and in line circuit **I2** control relay **B2r** is operated in an analogous manner as control relay **B1r**. Due to this the terminals **Y11**, **Y12** are connected to station **S3** via contacts **d11**, **d12**, contacts **b23**, **b24** in their work position and contacts **b33**, **b34** in their rest position. Inhibiting relay **G2r** is also energized as described above so that no direct calls can reach station **S2**. Finally, no direct calls can reach station **S3** since inhibiting relay **G3r** being energized as follows: battery, winding of relay **G3r**, contacts **f13**, **b112**, **b28**, ground. This relay connects test terminal **Y33** to battery via contact **g31** and resistor **R31** due to which this test terminal is rendered busy.

In case the control key **K1** is actuated when control keys **K2** and **K3** have already been actuated calls made to station **S1** are obviously not to be diverted since they would again arrive in this station. Such a connection in cascade of the three stations **S1**, **S2** and **S3** is prevented by the inhibiting circuit **M** since when all the control keys **K1**, **K2** and **K3** are actuated the relays **B1r**, **B2r** and **B3r** are all energized so that the battery is disconnected from leads **m2** and **m3** and particularly from lead **m1** due to which the operation of interconnecting relay **D1r** is prevented. When the subscriber in station **S1** then lifts his telephone handset in order to divert calls towards this station he will not receive an acknowledgement signal, since the operation of the acknowledgement relay **C1r** is also prevented by the inhibiting circuit **M**.

In the above the interconnection of called station **S1** and station **S2** or **S3** has been described in detail. Obviously each of the latter stations can be connected in an analogous manner to any of the other stations.

In the switching system shown each line circuit is normally disconnected from the exchange by the make contacts of an interrupting relay **E1r**, **E2r**, **E3r** due to which this relay has to be operated in case of incoming calls and a repeater relay **A1r**, **A2r**, **A3r** has to be energized in case of outgoing calls.

Instead of proceeding in this manner one could also replace in each station e.g. in **S1**, the make contacts of the interruption relay **E1r** by break contacts of the seizure relay **F1r**. In this case it would however be necessary to provide in each station additional circuits preventing a ringing signal from operating the ringing circuit of the subset included in this station **S1** and preventing from energizing the control relay **B1r** included in the line circuit of this station **S1**. Indeed, without such additional circuits, a ringing signal applied to terminals **Y11**, **Y12** always arrives in station **S1**, i.e. even when control key **K1** is actuated, and is applied to this station until seizure relay **F1r** is energized by the seizure signal applied to terminal **Y13**. In case control key **K1** is actuated this may give rise to an erroneous operation since a person present in station **S1** may hook off his handset and so interrupt the ringing signal which will hence never reach station **S2**. Consequently, the call announced by the ring-

ing signal is not at all diverted to station **S2** although control key **K1** has been actuated. Such an erroneous operation is prevented by a control key **K1** which not only applies a ground to a line wire but also interrupts the ringing circuit of the subset included in station **S1**.

5 Another erroneous operation is that when control key **K1** is not actuated an above ringing signal may operate the control relay **B1r** which should only be energized when control key **K1** is actuated. In order to prevent such erroneous operation a high impedance circuit for this ringing signal has to be branched between the line wire **b1** and the winding of this control relay.

Since the interruption of the ringing circuit of a subset by a control key necessitates this subset to be modified and due to the high impedance circuit being relatively expensive, the shown solution has been preferred over the additional circuits even though repeater relay **A1r** is not necessary when using the latter circuits.

15 While the principles of the invention have been described above in connection with specific apparatus, it is to be clearly understood that this description is made only by way of example and not as a limitation on the scope of the invention.

20 What is claimed is:

25 1. A switching system for diverting calls from a first line to a second line comprising two subscriber stations connected to corresponding line circuits, switching means coupled to the line circuit of one of said stations to cause calls directed to said one station to be diverted towards the associated station, said switching means including a manual control coupled to a control relay in the line circuit, means interconnecting said two stations through normally inoperative interconnection circuits, said switching means including a seizure relay which is energized in response to a seizure signal in the line circuit indicating a call to the one station, and an interconnecting circuit between said one and associated stations including an interconnecting relay which is operated when simultaneously said control and said seizure relays are energized, said energized control and seizure relays of the line circuit of said called station operating an inhibiting relay included in the line circuit of said associated station, the thus operated inhibiting relay preventing the seizure relay included in the line circuit of said associated station from being operated upon a seizure signal being applied thereto.

30 2. A switching system according to claim 1 in which the manual control provides a control signal in the form of a ground which is applied to operate the control relay.

35 3. A switching system according to claim 1 in which the line circuit of said first one of said stations includes means for supplying a request acknowledgement signal in response to closure of the hookswitch, an acknowledgement relay operated when simultaneously the said control signal and the request acknowledgement signal are generated in said one station, said acknowledgement relay applying an acknowledgement signal from an acknowledgement signal generator to said one station.

40 4. A switching system according to claim 1, in which the line circuit of each station includes an interrupting relay which normally disconnects this station from the exchange wherein said seizure signal is generated and which when operated connects this station to said exchange, said interrupting relay being operated when simultaneously said control relay and said seizure relay of said line circuit are released and operated respectively.

45 5. A switching system according to claim 4, in which said line circuit further includes a repeater relay operated when simultaneously said control relay is not operated and the line loop in the station is closed, the thus operated repeater relay repeating the closure of said loop notwithstanding the released condition of said interrupting relay.

50 6. A switching system according to claim 5, including **m** stations each interconnected with the next by one of said interconnecting circuits, and an inhibiting circuit asso-

ciated with each of the first $m-1$ stations, each inhibiting circuit being normally inoperative and allowing for the diversion of a call to the next station through up to $m-1$ interconnecting circuits in cascade, said inhibiting circuits being made operative individually when a control signal is generated in the first $m-1$ stations, and said inhibiting circuits in operative condition preventing the seizure relay of the same station from being energized.

7. A switching system according to claim 6, in which, when a call is to be diverted from said called station to another station through a cascade of up to $m-1$ interconnecting circuits, the first interconnecting circuit extending between said called station and said associated station is made operative by the operation of said interconnecting relay included in said first interconnecting circuit, whereas each of the other interconnecting circuits of said cascade is made operative when said control relay included in the line circuit of the corresponding station from which the interconnecting circuit emanates is energized.

8. A switching system according to claim 7 in which said inhibiting circuits in operative condition prevent said interconnecting relays from being energized when the control relays of the line circuits of all said m stations are energized.

5 9. A switching system according to claim 8 in which said energized seizure and control relays of said called station operate the inhibiting relays of the line circuits of said other station and of the stations between said called and other station, each operated inhibiting relay preventing the operation of the seizure relay included in the same line circuit.
